US00D651095S

(12) United States Design Patent
Kerr et al.(10) Patent No.: US D651,095 S
(45) Date of Patent:  Dec. 27, 2011(54) PET FOOD SUPPLEMENT PACKAGE

(75) Inventors: George Scott Kerr, Mason, OH (US);
Gregory Dean Sunvold, Lewisburg, OH (US); Lawrence Andrew Schumacher, Trenton, OH (US); David William Schuller, Lebanon, OH (US); Robbert H. Ter Haar, Dayton, OH (US); Gary J. Kohlman, Terrace Park, OH (US)

(73) Assignee: The Procter & Gamble Company, Cincinnati, OH (US)

() Term: 14 Years

(21) Appl. No.: 29/392,480

(22) Filed: May 23, 2011

Related U.S. Application Data

(62) Division of application No. 29/381,568, filed on Dec. 21, 2010, now Pat. No. Des. 640,564, which is a division of application No. 29/361,951, filed on May 18, 2010, now Pat. No. Des. 631,757, which is a division of application No. 29/346,244, filed on Oct. 29, 2009, now abandoned, which is a division of application No. 29/320,852, filed on Jul. 7, 2008, now Pat. No. Des. 605,527.
